(57) **CLAIM**

The ornamental design for a surgical drape, as shown and described.

DESCRIPTION

FIG. 1 is a perspective view of a top side of a first embodiment of a surgical drape in accordance with my new design;

FIG. 2 is a perspective view of a bottom side thereof;

FIG. 3 is a plan view of the top side thereof;

FIG. 4 is a plan view of the bottom side thereof;

FIG. 5 is a side elevation view thereof;

FIG. 6 is a back side elevation view thereof;

FIG. 7 is a front side elevation view thereof;

FIG. 8 is a perspective view of a top side of a second embodiment of a surgical drape in accordance with my new design;

FIG. 9 is a perspective view of a bottom side thereof;

FIG. 10 is a plan view of the top side thereof;

FIG. 11 is a plan view of the bottom side thereof;

FIG. 12 is a side elevation view thereof;

FIG. 13 is a back side elevation view thereof;

FIG. 14 is a front side elevation view thereof;

FIG. 15 is a perspective view of a top side of a third embodiment of the surgical drape in accordance with my new design;

FIG. 16 is a perspective view of a bottom side thereof;

FIG. 17 is a plan view of the top side thereof;

FIG. 18 is a plan view of the bottom side thereof;

FIG. 19 is a side elevation view thereof;

FIG. 20 is a back side elevation view thereof; and,

FIG. 21 is a front side elevation view thereof.

(Continued)

The broken lines in the figures illustrate portions of the surgical drape that form no part of the claimed design. The side elevation view of the surgical drape represent the right and left sides of the surgical drape, that mirror each other. Further, the evenly dashed broken lines depict portions of the article and form no part of the claim. The unshaded surfaces adjacent evenly dashed broken lines form part of the claim. The dash dot dot dash lines depict the claim boundary and do not form part of the claim. The surfaces outside of the claim boundary form no part of the claim.

1 Claim, 15 Drawing Sheets

Related U.S. Application Data

which is a continuation-in-part of application No. 15/493,700, filed on Apr. 21, 2017, now Pat. No. 10,905,614.
